(57) **CLAIM**

We claim the ornamental design for a male zipper track portion for resealable bag, as shown and described.

DESCRIPTION

FIG. 1 is a perspective view of a male zipper track portion for resealable bag, showing our new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;

FIG. 7 is a bottom plan view thereof;
FIG. 8 is a sectional view taken along line 8-8 of FIG. 6;
FIG. 9 is a sectional view taken along line 9-9 of FIG. 6;
FIG. 10 is a reference view thereof shown with environment; and,

FIG. 11 is a reference view thereof showing a configuration of use with the environment.

The broken lines in the drawings illustrate environment which do not form a part of the claimed design.

1 Claim, 7 Drawing Sheets
